SWIMMER'S FOOT FIN

Kazuo Tabata, Tokyo, Japan, assignor to Kabushiki
Kaisha Tabata (also known as Tabata Co., Ltd.), Tokyo,
Japan

Filed Sept. 14, 1972, Ser. No. 289,100

Term of patent 14 years

Int. Cl. D21—02

U.S. Cl. D34—44

FIG. 5FIG. 6FIG. 7FIG. 8FIG. 1 is a top plan view of a swimmer's foot fin incorporating my new design.

FIG. 2 is a bottom plan view thereof.

FIG. 3 is a front view thereof.

FIG. 4 is a rear view thereof.

FIG. 5 is a side elevational view thereof.

FIG. 6 is a perspective view thereof.

FIG. 7 is a sectional view thereof taken along a plane corresponding to line 7—7 of FIG. 1.

FIG. 8 is a transverse sectional view taken along a plane corresponding to line 8—8 of FIG. 1.

I claim:

The ornamental design for a swimmer's foot fin, substantially as shown.
